UNITED STATES PATENT OFFICE.

RALPH T. WILLIAMS, OF CHICAGO, ILLINOIS, ASSIGNOR TO BODINE ELECTRIC COMPANY, OF CHICAGO, ILLINOIS, A CORPORATION OF ILLINOIS.

RADIO TUNING INDUCTANCE.

Application filed October 6, 1926. Serial No. 139,905.

My invention relates to inductances of the class commonly employed as radio tuning coils, and to means for supporting such inductances.

5 In some of its general objects, my invention provides an inductance of this class which will amplify with fair uniformity over a wide range of wave length, such as the entire range now employed by broadcasting stations; which will introduce a quite low loss; which will be quite compact, and in which the resulting magnetic field will be so concentrated that the inductance can easily be shielded from other inductances 10 and against outside influences.

In some further aspects, my invention provides an inductance which can readily be supported from a part of the inductance spaced from the major portions of the inductance winding, and which can readily be used in a compact tandem arrangement to afford a "tickler" coil. It also provides an inductance winding particularly adapted for the convenient supporting and rotating of 20 the inductance, and one in which the part of the winding which facilitates such supporting is arranged so as to reduce the longitudinal dimension of the inductance and so as to permit contiguity of the consecutive 25 wire portions in each of the two main parts of the inductance.

More particularly, my invention provides an inductance consisting of two parallel coils connected by crossed wire portions in 30 "figure 8" formation, with the consecutive turns in each coil contiguous and with the height of the cross-connecting wire portions equal to that of each coil. For this purpose, my invention provides a novel arrangement of these cross-connecting wire 35 portions, a novel method of winding the entire inductance; and provides a novel disposition of the wire parts which form each of a plurality of counterpart and superposed 40 sections of the inductance, whereby the two main coils are wound in opposite directions as inductances whose magnetic fields reinforce each other, and whereby parts of the connections between these main coils form 45 a non-inductance interposed coil.

Furthermore, my invention provides a novel and easily attached mounting for supporting such an inductance and for supporting the needed wire terminals. Still 50 further and also more detailed objects will

appear from the following specification and from the accompanying drawings, in which drawings

Fig. 1 is an elevation of a radio tuning inductance embodying my invention. 60

Fig. 2 is a plan view of the same.

Fig. 3 is a plan view of the same inductance before the support and the wire terminals are attached to it.

Fig. 4 is an elevation of the supporting 65 and terminal-carrying member of the radio tuning coil of Figs. 1 and 2, taken at right angles to Fig. 1.

Fig. 5 is a diagrammatic view showing the winding of one of the superposed and 70 counterpart coil sections, with the mandrel on which the wire is wound shown in section.

Figs. 6, 7, 8 and 9 are diagrams respectively showing the consecutive parts of the 75 coil section of Fig. 5.

Fig. 10 is a perspective view of a tickler coil embodying my invention. 75

While the inductances of my invention may be employed with equal advantage for a large variety of purposes, it is particularly 80 adapted for use as a radio frequency tuning coil or for a three-circuit tuning coil which employs a tickler coil. Hence I am illustrating and describing my invention in such embodiments although I do not wish to be 85 limited to any particular employment of my invention.

Referring first to Fig. 5, this shows the two cylindrical mandrels 1 and 2 around which the main wire portions are wound 90 with the direction of the winding around one mandrel opposite to that around the other mandrel, the two mandrels preferably being equal in diameter and having their axes parallel. In the ordinary "figure 8" 95 inductance as heretofore employed, the wire portions leading from each mandrel to the other are disposed as straight tangents to both mandrels, so that these wire portions all intersect along a single axis parallel to 100 the axes of the two mandrels, which axis of intersection is midway between the mandrel axes if the mandrels are of equal diameter. Consequently, there are two superposed crossed wire portions at this axis of intersection for every complete "figure 8" layer 105 of the winding. If the wires in the arcuate parts of the winding are contiguous, the intersecting wire portions will be double the heights of these arcuate parts which 110

form the main coils, thereby doubling the height of the inductance and the space required for it, and this same doubled height of the inductance will be needed if the consecutive main arcuate wire parts of each coil are spaced from each other to make the main coils equal in height to the crossed connecting wire portions. In either case, the spacing of such wire parts longitudinally of the inductance reduces the efficiency of the inductance and doubles the space occupied by the inductance.

So also, if the consecutive arcuate wire parts of the main coils are contiguous, so that the crossed wire portions exceed the height of the main coils, the magnetic field is greatly distorted, thereby reducing the efficiency of the inductance, making it more difficult to shield the inductance, and causing distortions in the periodic current waves.

To overcome these serious disadvantages of an ordinary "figure 8" winding, I interpose an intermediate mandrel 3 between the main mandrels 1 and 2 when winding my inductance. This intermediate mandrel is preferably considerably smaller in diameter than the mandrels 1 and 2 and equidistant from the main mandrels, and preferably has its axis parallel to and in a common plane 4 with the axes of the main mandrels.

Then I wind the wire around the three mandrels in counterpart sections as traced for one section diagrammatically in Figs. 6 to 8 inclusive, and as shown compositely in Fig. 5, the wire portions in Fig. 5 being slightly spaced from the mandrels to avoid confusion. Beginning at the top of the intermediate mandrel 3, I wind the wire clockwise around the mandrel 2, and carry it under the intermediate mandrel 3 as per Fig. 6. Then I wind the wire counter-clockwise around the mandrel 1, pass it under the intermediate mandrel 3 as in Fig. 7, wind it clockwise around the mandrel 2 and again pass it above the intermediate mandrel as shown in Fig. 8. For the final part of the section, I wind the wire counter-clockwise around the mandrel 1 and bring it over the top of the mandrel 3 or to the starting point of the winding as shown in Figs. 5 and 6.

In thus winding each of the counterpart wire sections which are superposed on each other longitudinally of the axes of the mandrels, and each of which sections includes two arcuate portions extending partly around one main mandrel, the connecting wire portions of the section are crossed at the four points designated in Fig. 5 respectively as A, B, C and D. These four points are substantially at the four corners of a square and are spaced from each other sufficiently so that the wire parts between them can be bent out of the general plane of the wire in that section of the coil. Consequently, by distributing the wire crossings

in this manner and by exerting a suitable pressure on the wire towards the previously wound portion (longitudinally of the axis of the mandrel 3) during the winding, I not only am able to have the overlapping main arcuate wire parts of the inductance contiguous, but also can keep the height of the crossed wire portions equal to the height of the said arcuate or main coil parts of the inductance.

By so doing, I can make the height (or axial length) of my inductance half of that required for the ordinary "figure 8" coil in which the connecting wires all cross along a single axis, and can obtain consecutively contiguous arcuate wire portions of such a length extending approximately 135 degrees around the axis of each main mandrel—as to produce an inductance of low loss and high efficiency. So also, I avoid the distortion of the magnetic field which occurs in an ordinary "figure 8" coil when the crossed wire portions exceed the height of the main coil portions, since the windings of my inductance are all disposed approximately in planes at right angles to the axes of the main coils, so that these main coils afford a closed magnetic circuit as shown by the dotted line 14 in Fig. 1, whereby the magnetic fluxes in the two main coils reinforce each other. Owing to this closed magnetic circuit and to the absence of a distortion of the magnetic field, I not only make my inductance of high efficiency, but also prevent stray magnetic lines. Hence my inductance requires comparatively little shielding.

Since the flow of current through my inductance at any moment is either in the direction in which the wire was wound or in a direction reverse to the winding, it will be evident from the drawings that the flow of current through the two main coils is in respectively opposite directions, but is in one direction throughout the length of each main coil. However, in the interposed auxiliary coil, the flow of current at opposite sides of the bore of this coil is in opposite directions circumferentially of this auxiliary coil, so that these portions of the winding neutralize each other in their inductive effect. Hence the interposed auxiliary coil is non-inductive and will neither distort the magnetic field of the main coils nor introduce a considerable loss.

After a continuous strand of insulated wire has been wound around the three mandrels to form any desired number of superposed sections each disposed as shown in Fig. 5, the resulting inductance is easily cemented into a rigid unit by applying colloidion or the like to the arcuate portions of the coils and the wire crossings at the points A and C, after which the completed inductance can be slipped off the mandrels.

When thus detached, the wire portions

connecting the intersections A, B, C and D with one another form an interposed auxiliary tube (shown in Figs. 3 and 5 as substantially octagonal in section) which tube can be used to good advantage in mounting the inductance. For such a mounting, Fig. 4 shows an insulating stem 5 of a length corresponding to the height of the finished inductance coil and of such a diameter as to slide readily into the bore of the said auxiliary tube. A foot-piece 6 is fastened to one end of the stem 5 by a screw 7 and has perforations 8 for receiving screws by which it may be secured to any support. After the stem 5 has been slid through the said auxiliary tube, the top of the inductance is clamped against the stem by an insulating cross-bar 9 which cross-bar is fastened to the stem by a screw 10. This cross-bar may also carry a pair of wire terminals 11 and 12 to which the ends of the inductance are connected. A similar cross-bar 13 of insulating material may also be interposed between the bottom of the inductance and the foot-piece 6.

However, the entire inductance need not be used as a single winding, but might have wire connections to different superposed parts each composed of a plurality of superposed wire sections wound as shown in Fig. 5, the making of the needed connections to such coil parts being so well known as to require no explanation or illustration here.

Moreover, my inductance need not be stationary, as its ease of mounting and unusual compactness make it advantageous also for use as a rotatable inductance. For example, two such inductances can readily be mounted with their axes in alinement and with one of them rotatable, thereby producing a very compact three-circuit tuning coil, such as that shown in Fig. 10. In that case, I may clamp one inductance to a shaft extending through the bore of a hollow stem which supports the other inductance.

However, I do not wish to be limited either to a particular mounting for my novel inductance nor to the details of the construction and arrangement above recited, since many changes might obviously be made without departing either from the spirit of my invention or from the appended claims.

I claim as my invention:

1. An inductance formed of a continuous wire wound to form two parallel tube portions of relatively reversed polarity connected by two intersecting pairs of crossed wire portions, the winding being such that the said crossed wire portions form an intermediate tube having its axis extending parallel to the axes of the aforesaid tube portions.

2. An inductance formed of a continuous wire wound to form two parallel main

tube portions in which the direction of winding is relatively reversed, and two pairs of connecting wire portions crossed so as to form a substantially quadrilateral intermediate tube, the wire parts forming each of the two main tube portions being contiguous and equal in height to the joint height of the wire portions forming the intermediate tube.

3. An inductance as per claim 1, in combination with a supporting member extending through the intermediate tube, and means associated with the supporting member and engaging opposite ends of the intermediate tube to clamp the intermediate tube to the supporting member.

4. A twin coil inductance formed of a continuous wire wound to form two axially parallel tube portions wound in relatively reverse directions connected by two intersecting pairs of crossed wire portions; each of the said crossed wire portions comprising two sets of connecting wire parts extending in a common general direction, and the connecting wire parts of each set being bowed away from those of the other set in a direction transverse of a plane extending through the axes of both the said tube portions.

5. An inductance formed of a continuous wire wound to form two parallel and relatively spaced main tubes of relatively reversed polarity connected by wire portions which also form a smaller-diametered and non-inductive intermediate tube having its axis parallel to the axes of the said main tubes, the winding being such that the connecting wire portions intersect consecutively along four axes consecutively spaced circumferentially of the intermediate tube.

6. An inductance formed of a continuous wire wound to form two parallel and relatively spaced main tubes connected by wire portions to a smaller-diameter intermediate tube which has its axis parallel to the axes of the said main tubes, the winding being such that the current flows in opposite directions in the two main tubes, and so that the flow of current is relatively reversed in every two consecutively superimposed wire parts of the intermediate tube, whereby the said main tubes are of reversed polarity and the intermediate tube is non-inductive.

7. An inductance formed of a continuous wire wound to form two parallel main tube portions connected by two pairs of wire portions crossed so as to form a substantially four sided intermediate tube, the winding being such that the current flows in relatively opposite directions through the said main tube portions, and so that the flow of current through opposite sides of the intermediate tube is in the same direction circumferentially of that tube.

8. An inductance composed of a continu-

- ous wire formed to constitute a plurality of counterpart superposed sections; each successive section comprising two superposed "figure 8" loops; each section having the intersection of the wire parts connecting the bights of the upper loop spaced in the general plane of the loop from the intersection of the wire parts connecting the bights of the lower loop.
10. An inductance formed of a continuous wire wound substantially in "figure 8" formation to form two parallel and spaced tubes; each tube having a main portion formed of contiguous wire parts corresponding in transverse section to more than half of a circle, the said wire parts of the said main portions of the two tubes being connected by connecting wire portions which cross one another to form an intermediate tube having the cross-over points spaced circumferentially of the intermediate tube, the said connecting wire portions being bent sufficiently out of the general plane of the said wire parts of the main tube portions which are connected by them, so that the intermediate tube is substantially equal in height to the said spaced tubes.
11. An inductance comprising a continuous winding formed of counterpart and superposed sections; each section comprising two pairs of superposed and alining arcuate wire portions, the winding of each such pair of arcuate portions being in the opposite direction from the winding of the other pair of arcuate portions, the axes of the said two pairs being parallel and the two pairs being connected by two pairs of connecting wire parts, the constituents of each said pair of connecting parts being spread apart at their middles to afford four crossings for the said connecting wire parts, whereby medial portions of the connecting wire parts form a four sided non-inductive tube, and whereby the two pairs of arcuate wire portions respectively form parts of two tubes of relatively reversed polarity.
12. An inductance as per claim 10, in which the superposed arcuate wire portions of each pair are contiguous to each other and respectively contiguous to arcuate wire portions of the next lower section, and in which the connecting wires are kinked out of the general planes of the arcuate portions connected by them to make the said tube equal in height to the height of each set of superposed arcuate wire parts.
13. An inductance comprising a continuous winding formed of counterpart and superposed sections; each section comprising two pairs of superposed arcuate wire portions, the axes of the said two pairs being parallel and the two pairs being connected by two pairs of connecting wire parts, the connecting wire parts of each pair terminating at superposed ends of the said arcuate parts, each pair of connecting wire parts extending in the general directions of tangents to the said arcuate parts and intersecting the common plane of the axes of all of the arcuate parts, and the said general directions of the two pairs of connecting wire parts being at an angle to each other.
14. An inductance composed of superposed counterpart sections in series with each other; each section comprising two superposed "figure 8" loops formed of a continuous strand of insulated wire, the wire portions connecting the arcuate parts of these loops being spread apart adjacent to their middle so that the cross-over points of the said connecting wire portions are spaced lateral from and consecutively spaced around an axis between and parallel to the axes of the two arcuate portions of each "figure 8" loop.

Signed at Chicago, Illinois, September 27th, 1926.

RALPH T. WILLIAMS.
